UNITED STATES PATENT OFFICE.

WILLIAM BAXTER, JR., OF JERSEY CITY, NEW JERSEY.

PNEUMATIC HAMMER.

935,634.

Specification of Letters Patent.

Patented Oct. 5, 1909.

Application filed March 12, 1906. Serial No. 305,635.

To all whom it may concern:

Be it known that I, WILLIAM BAXTER, Jr., a citizen of the United States, residing in Jersey City, in the county of Hudson and State of New Jersey, have invented certain new and useful Improvements in Pneumatic Hammers, of which the following is a specification.

The present invention relates to pneumatic hammers or similar reciprocating tools, and the object of the invention is to provide improved means for regulating the force of the blow and the velocity of the hammer.

Another object of the invention is to so construct the actuating valve that it will at the same time act as a throttle valve.

Other and further objects will appear from the following specification and will be more particularly pointed out in the annexed claims.

In the accompanying drawing—Figure 1 is a longitudinal section through the entire hammer; Fig. 2 is a section through the valve chamber, on the line *a—a*, Fig. 1, the valve and the parts co-operating therewith being removed; Fig. 3 is a section on the line *b—b*, Fig. 1, with the valve removed; Fig. 4 is a section on the line *c—c*, Fig. 1; Fig. 5 is a bottom view of the cylinder cap; Fig. 6 is a side view of Fig. 5; Fig. 7 is a top view of Fig. 5; Fig. 8 is a side view of the actuating valve, partly in section; Fig. 9 shows one of the stop plungers, and Fig. 10 shows a modified form of plunger and one of the valve chamber heads.

1 is a casing which is formed in the shape of a handle at the upper end, and at the lower end is shaped to receive the valve and the upper end of the working cylinder.

2 and 3 represent the working cylinder which preferably is made in two parts secured together by screws 58, to simplify the construction of the ports 30 and 31, but the cylinder may be made solid and holes may be drilled therein to form the ports.

4 is the plunger and 5 is the combined actuating and throttle valve. The valve chamber is preferably provided with a lining 6 to increase the durability of the tool.

7 and 8 are valve chamber heads, and 9 and 10 are stop plungers having stems 59 and enlarged inner ends 37 provided to limit the movement of the valve in either direction.

12 is the lower head of the working cylin-

der, and 13 is the shank of the tool which is driven forward by the lower end 51 of the plunger 4.

14 is the inlet through which compressed air passes to the tool, 15 and 16 are levers through which the operator moves the plunger 10, and 17, 18, are levers through which he moves the plunger 9, all these levers being pivoted on studs 19.

20 and 21 are recesses in the sides of 1, in which the ends of 9 and 10 are located so as to be protected against external injury.

22 is the large end of the valve chamber and 23 is the small end which is provided with an abutment for the head 8.

24, 25, and 26, are ports provided in the valve chamber and 11 is the cylinder cap which is provided with ports 27 and 28, in its upper side.

29 is a projection on the lower side of the cap 11 which serves to make a tight joint against the end of the cylinder, and also to form a port 54.

30 and 31 are ports in the cylinder, the first connecting the lower end 52 with the port 54, and the latter connecting an annular port 34 surrounding the cylinder with a port 57 provided in the wall of the cylinder.

32 is an annular port surrounding the cap 11 and connecting the port 27 with the chamber 33 into which the inlet 14 opens.

35 and 36 are ports that serve to connect the port 34 with a space 43 between the head 7 and the left end of the valve 5.

37, 38, are enlarged ends of the stop plungers 9, 10 that fit close enough into the depressions in the ends of the valve to act as cushions and thus prevent the valve from striking violently against them, but they do not fit air tight.

38, 39 and 40 are the piston portions of the valve 5, which are connected with each other by necks 41, 41. The portions 38 and 39 are of the same diameter while the portion 40 is of less diameter than the other portions.

42 is a small port that connects the port 28 with the space 43, and 44 is an exhaust port that connects with the port 24 when the valve moves far enough to the left.

45 are holes through cap 11 that connect the port 28 with the port 54.

46 are pins and 47 are holes provided to hold the cap 11 in a fixed position with relation to the casing 1.

48 is a cylindrical depression in the upper

end of the plunger 4 made to fit snugly around the neck 56 of the cap 11.

49 is a neck turned at the lower end of the plunger 4, just above the head 50, for the purpose of connecting the port 57 with an exhaust port 53, when the plunger 4 is in the upper position.

The operation of the hammer is as follows: If the levers 15, 16 and 17, 18 are in the position shown in Fig. 1, and the inlet 14 is connected with a source of compressed air, the hammer will use the maximum amount of air and will make the maximum number of strokes in unit time and strike the maximum blow. The levers 17, 18 are normally in the position shown in Fig. 1, while the levers 15, 16 are held in this position by the thumb of the operator and against the action of a spring 55. The stop plungers 9—10 are forced outwardly against levers 18 and 15 respectively by spiral springs, surrounding the stems 59 as clearly shown. When it is desired to stop the tool, the operator releases his hold on the lever 16 and the outer end of the lever is thrown upward by the spring 55, and this movement swings the lower end of the lever 15 to the right until the enlarged end 37 of the plunger 10 lies against the valve 5 and prevents the movement of the valve. The compressed air coming from the source 14 passes through the chamber 33 and the ports 32, 27 and 26 to the space between the pistons 39 and 40 of the valve, and as the former is larger than the latter, there is an excess of pressure acting to move the valve to the left, but it cannot move until the operator depresses the lever 16. If the lever 16 is depressed to the position shown in Fig. 1, the valve 5 will

40 be free to move to the left until it strikes the enlarged end 37 of the plunger 10. When it so moves, valve piston 39 will pass to the left and thus open connection between the ports 25 and 26, and the compressed air will 45 pass to the upper end of the cylinder. If the plunger 4 is at the top of the cylinder, it will be forced down to the position shown in Fig. 1, by the compressed air. As soon as it is far enough down to uncover the port 57, 50 the air will pass to the port 31, thence through the ports 34, 35 and 36 to the space 43 between the head 7 and the valve piston 38. The pressure on the left side of the piston 38 will now balance the pressure on

55 the right side of the piston 39 and the unbalanced pressure against the left side of the piston 40 will, therefore, force the valve to the right to the position shown in Fig. 1. When the valve reaches this position, the 60 compressed air in the upper end of the cylinder will pass through the ports 25, 24, 28 and 30 to the space 52 at the lower end of the cylinder, and if there is air tight connection between the shank 13 and the cylinder end, the pressure will force the plunger

4 upwardly, as the end 50 is larger than the upper end. When the plunger 4 has been forced nearly to the uppermost position the lower edge of the head 50 uncovers the exhaust port 53 and permits the air to escape 70 from the cylinder. At the same time, the port 53 is connected with the port 57, through the neck 49, so that the compressed air in the space 43 is also exhausted and thus the pressure is relieved at this end of 75 the valve, and the pressure on the right side of the piston 38 is unbalanced so that the valve is now moved to the left, ready to repeat the cycle.

From the above description, it will be understood that if the valve is not perfectly air tight, the compressed air which has passed to the space 43 through the port 57, will soon leak out after the port 57 is covered by the plunger 4 on the return stroke, hence the 85 valve would be forced over to the left before the plunger 4 reached the upper position. The result of this would be that the full stroke of the plunger 4 would not be obtained. To prevent this occurrence, the 90 small port 42 is provided which connects the port 28 and the space 43 so that the pressure in the space 43 may be maintained after the port 57 is covered by the plunger 4 on the upstroke. It will also be seen that if the 95 valve piston 40 does not fit perfectly, the space between the piston 40, and the head 8 would gradually be filled with compressed air and then the valve would not operate. To prevent this trouble, the stop plunger 9 100 does not fit tightly against the head 8, but portions are cut away in the head 8 at the upper side of the plunger 9, as shown in Fig. 1.

The amount of air that passes to the working cylinder, determines the force with which the plunger 4 is driven forwardly, that is, the force of the blow upon the shank 13. The amount of air is controlled by the extent to which the port 25 is uncovered by 105 the valve when it moves to the left, and this movement of the valve is controlled by the position of the stop plunger 10; hence, the force of the blow can be increased or decreased by the extent to which the operator 110 depresses lever 16. Thus through the proper manipulation of lever 16, the force of the blows struck by the hammer can be regulated.

The velocity at which the plunger 4, will 120 move on the backward stroke, that is, from the head 12 to the cap 11, depends on the velocity with which the compressed air can pass from the upper to the lower end of the cylinder, and this velocity will depend upon the extent to which the port 25 is uncovered by the valve 5 when the valve moves to the right. It will be seen that if the operator 125 raises the lever 17, the stop plunger 9 will be forced to the left and the opening of the 130

port 25 will be reduced, hence, the more the lever 17 is raised, the more the port 25 will be closed, and the slower the velocity of the plunger 4 on the backward stroke.

- 5 One serious objection to pneumatic hammers is that they vibrate violently. The cause of this vibration is that the momentum of the plunger 4 on the backward stroke has to be absorbed by the inertia of the tool.
- 10 The momentum on the forward stroke does not jar the tool because it is all expended upon the shank 13 of the working tool. To reduce the jarring of the hammer to a minimum, it is necessary to reduce the velocity 15 of the plunger 4 on the backward stroke as much as permissible. To make the blow of the plunger 4 upon the shank 13 as effective as possible, it is necessary to let the compressed air have free access to the cylinder 20 of the down stroke or forward stroke, and to accomplish this, it is necessary that the valve 5 opens the port 25 as wide as practicable to allow the required amount of air to pass into the cylinder. If the movement of 25 the valve 5 were controlled entirely by the position of the plunger 10, it is evident that the rapidity of the strokes would vary with the force of the blows struck by the plunger 4, both increasing and decreasing together.
- 30 By providing the stop plunger 9, the rapidity and the force of the blows can be varied independently; thus if it is desired to strike with the maximum force, but with a long interval between the blows, the result can be 35 accomplished by depressing the lever 15 to the lowest position, which will produce the maximum blow, and by drawing the lever 17, upward which will reduce the rapidity of the strokes.
- 40 To reduce the vibration of the tool as much as possible, the extent to which the port 25 is opened when the parts are in the position shown in the drawing, that is when the ports 24 and 25 are connected, is determined experimentally, the opening being 45 gradually increased until the jarring becomes all that is considered admissible. For any rapidity of strokes below this limit, the vibration will be decreased. If it is desired 50 to arrange the tool so that the movement of the plunger 4 may be actually stopped by moving the lever 17, the levers 17 and 18 are arranged in such a manner that they can move the plunger 9 so far to the left that the 55 valve will not open the port 25 when moved to the right; hence, the air in the upper end of the cylinder cannot pass to the lower end. If it is not desired to have the tool operate in this way, but merely to have the movement 60 of the lever 17 acting to reduce the rapidity of the strokes, a suitable stop is provided to limit the movement of lever 18. The simplest way to provide such a stop is to make the distance between the upper end of 65 the lever 18, and the handle 1 such that when

the lever strikes the handle, the rapidity of the strokes is reduced to minimum.

From the foregoing explanations, it will be seen that with my improved hammer, it is possible to strike the hardest blow with 70 the lowest rapidity of strokes, or the lightest blow with the greatest rapidity, or vice versa.

When the levers 17, and 18, are provided, the operator can vary the rapidity of the 75 strokes at will; but in many cases this is not necessary, it being sufficient to be able to set the tool to operate at a given velocity. In such case, the levers 17, 18, are discarded and the stop plunger 9 and the head 8 are made 80 as shown in Fig. 10 so that the plunger may be set in any desired position. To hold it securely in this position, a check nut 61 is provided.

The office of the port 44 is to provide an 85 outlet for the air from the space 52 under the plunger, when the latter on the forward stroke has moved far enough to make the head 50 cover the port 53. After this port is covered the air escapes through the port 90 30 and the valve chamber to the exhaust port 44.

It will be noticed particularly that the valve 5 plays the double part of an actuating 95 valve and a throttle valve, but it is to be understood that my invention is not restricted to this arrangement, because the valve 5 in conjunction with the levers 17 and 18 and the plunger 9 will act to reduce the rapidity 100 of the strokes even when a separate throttle is used.

It will be easily understood that the plunger 10 could be permanently secured to the head 7 in the position in which it is shown in Fig. 1, or it could be made integral with the head, and the compressed air could be admitted to the tool through any of the various forms of throttle valves commonly used, such valve being operated by the lever 16, or in any other desired manner. Thus a simple stop cock in the inlet 14 could 105 be made to answer the purpose of a throttle. 110

In order that a pneumatic hammer of this type may deliver the hardest blow possible at the available pressure of the compressed air, it is necessary that the construction be such that the loss of pressure between the supply pipe and the cylinder be reduced to minimum. As the movement of the plunger 4 on the forward stroke is resisted only by 115 the small frictional resistance and a very slight back pressure, it will accelerate its velocity very rapidly, and thus reduce the pressure materially if the ports connecting the valve with the cylinder are long. In the usual forms of hammers in which the throttle valve is placed a considerable distance from the cylinder, the loss of pressure is great, and increases as the opening 120 through the valve is reduced, to give lighter 125

130

blows. If the valve is placed as close to the cylinder as possible, as in Fig. 1, the pressure acting on the plunger 5, at the beginning of the stroke, will be nearly the full pressure, no matter how much the supply of air may be throttled, because the clearance space within the valve chamber and the ports connecting with the cylinder, is so small that it can be filled without making a material reduction in the pressure in the port 26, and this pressure is the same as that at the inlet 14, owing to the large size of the connecting passages 32, 33 and 27.

Having described my invention, what I claim as new is:

15. 1. A pneumatic tool having an actuating valve operated by the compressed air in a continuously automatic manner and means movable independently of the valve controlling said valve whereby it is adapted to perform the function of a throttling valve.
20. 2. In a pneumatic tool, the combination with the reciprocating plunger, of an actuating valve operated by the compressed air in a continuously automatic manner, and arranged to vary the velocity of the plunger during the return stroke, and means whereby the valve is adapted to perform the function of a throttling valve.
25. 3. In a pneumatic tool, the combination with the reciprocating plunger, of an actuating valve operated by the compressed air in a continuously automatic manner and adapted to control the velocity of the plunger on the return stroke, resiliently mounted means for varying the stroke of said valve while in action, and means whereby the valve is adapted to perform the function of a throttling valve.
30. 4. In a pneumatic hammer, the combination with the working cylinder, of an actuating valve arranged to admit compressed air to the upper end of the cylinder and to permit the transfer of such air from the upper to the lower end of the cylinder, and means whereby the valve is adapted to perform the function of a throttling valve.
35. 5. In a pneumatic hammer, the combination with the working cylinder, of a combined throttle and actuating valve arranged to admit compressed air to the upper end of the cylinder and to transfer such air from the upper to the lower end of the cylinder, and the valve controlling the rate of flow during the transfer, and resiliently-mounted means movable relatively to the valve and under the control of the operator to vary the action of the valve during the operation of the hammer.
40. 6. In a pneumatic hammer having a reciprocating operating valve actuated by the compressed air, means movable relatively to the valve for controlling the travel of the valve in such manner as to permit the throw

to be modified at will during the operation 65 of the hammer.

7. A portable pneumatic hammer provided with an actuating valve placed directly above the cylinder end, said valve being reciprocated continuously by the pressure fluid while the tool is in action; and means to enable the valve to act as a throttle when the tool is not in action.

8. In a pneumatic hammer having a reciprocating operating valve actuated by the 75 compressed air, means actuated independently of the valve for controlling the movement of the valve in either direction independently while the hammer is at work.

9. In a portable pneumatic hammer, a 80 working cylinder and striking plunger; an operating valve placed directly above the end of the cylinder, said valve being adapted to reciprocate continuously under the action of the pressure fluid; means operable independently of the valve whereby it is adapted to control the velocity of the plunger during the return stroke; and means whereby the valve acts as a throttle when the tool is not in action.

10. In a pneumatic hammer having compressed air circulating between one end of the working cylinder and the other, through suitable ports, a valve for controlling the rate at which the air circulates, and means 95 actuated independently of the valve for modifying the action of the valve.

11. In a portable pneumatic hammer, a working cylinder and striking plunger; an operating valve located directly above the 100 cylinder end, said valve being reciprocated continuously by the pressure fluid while the tool is in action, means acting independently of the valve for instantly varying the throw of the valve in either direction while the tool 105 is in action, said means enabling the valve to act as a throttle when the tool is not in action.

12. In a pneumatic hammer, the combination with the working cylinder, of a reciprocating operating valve actuated by the compressed air and adapted to control the flow of air from one end of the cylinder to the other, and means acting independently 110 of the valve for varying the movement of the valve during the movement thereof.

13. A pneumatic hammer having a working cylinder, an automatically actuated valve directly above the cylinder; and means actuated independently of the valve, whereby said valve is adapted to perform the functions of a throttling valve.

14. In a compressed-air actuated hammer, the combination with a working cylinder, the plunger, and passages communicating with the upper end of the cylinder and establishing communication between the ends of the cylinder; and means actuated in-

dependently of the valve to modify the movement of said valve while in motion and change the rate of flow of the pressure medium to the upper end of the cylinder and 5 from the upper to the lower end of the cylinder.

15. In a pneumatic hammer, having an automatic operating valve continuously and automatically actuated by the compressed 10 air, a pressure-controlled sliding stop adapted to limit the movement of the valve in one direction and another similar stop to limit the movement in the opposite direction, one of said stops being further adapted 15 to start and stop the hammer.

16. In a pneumatic hammer, having a continuously automatic actuating valve, stops adapted to slide axially in the direction of 20 movement of the valve, and means whereby the stops are held in any desired position subject to the will of the operator.

17. In a pneumatic hammer having a continuously automatic actuating valve, stops adapted to slide axially in the direction of 25 movement of the valve, means whereby the stops are held in any desired position so as to limit the throw of the valve in either direction, and means for adjusting the position of one of the stops.

30. 18. In a pneumatic hammer having a continuously automatic actuating valve, stops adapted to slide resiliently in the direction of movement of the valve, means whereby the stops are held in any desired position so 35 as to limit the throw of the valve in either direction, and means for varying the positions of said stops independently.

19. In a pneumatic hammer the combination of a working cylinder, a valve chamber 40 to which the compressed air has access, a continuously acting pressure-actuated valve within said valve chamber, controlling the admission of pressure medium to the working cylinder, and means actuated at will 45 independently of the valve defining the movement of said valve and causing the valve to throttle the flow of pressure medium.

20. A pneumatic hammer provided with 50 two actuating levers arranged to be operated by the fingers of the operator, one of said levers acting to control the force of the blows struck by the hammer, the other of said levers acting to control the rapidity 55 of the blows, and stops moved by said levers, arranged to slide freely in the path of the actuating valve to limit the throw of the valve in either direction.

21. In a portable pneumatic hammer having 60 an operating valve that is reciprocated by the pressure fluid; means for varying the throw of the valve in either direction, said means being constructed and arranged to be operated by the fingers on that hand of the operator that grasps the handle of the tool,

and comprising means adapting the throw of the valve in either direction to be instantaneously varied independently of the throw in the other direction and by a movement of the operator's fingers. 70

22. A portable pneumatic hammer provided with but a single valve, and means actuated independently of the valve for holding said valve in the closed position to stop the hammer; said valve being constructed 75 and arranged to reciprocate continuously when released and acted upon by the pressure fluid.

23. A portable pneumatic hammer having a single valve, stops, between which, the 80 valve when released, reciprocates continuously under the influence of the pressure fluid; and means for moving one of said stops to hold the valve against movement under the pressure fluid and thereby arrest 85 the reciprocation of the valve, and stop the action of the hammer.

24. In a portable pneumatic hammer having a plunger, ports controlling the plunger, a combined operating and throttle valve, 90 controlling said ports, stops, between which the valve reciprocates, valve controlling ports opened and closed by the movement of the valve, whereby it reciprocates continuously under the pressure fluid, one of said 95 stops being movable to arrest the valve short of its port opening position in one direction, whereby the valve is held stationary by the pressure fluid and the hammer is stopped; and the other stop being movable to arrest 100 the movement of the valve in the other direction, in position in which it partly opens the plunger controlling ports, whereby the force of the blow is modified.

25. In a portable pneumatic hammer a 105 combined operating and throttle valve adapted to be reciprocated continuously between movable stops by the pressure fluid and means mounted in the handle of the tool by means of which the position of either one 110 of the movable stops may be instantly changed during the action of the tool in such manner as to vary the velocity of the striking plunger.

26. In a portable pneumatic hammer an 115 operating valve adapted to be reciprocated between two movable stops by the pressure fluid; means actuated independently of said stops for instantly changing the position of each one of the stops; said means being actuated by the hand of the operator.

27. In a pneumatic hammer a combined 120 throttle and automatic operating valve adapted to be reciprocated continuously by the pressure fluid during the action of the tool; said valve being positioned directly above the cylinder in such manner as to reduce to a minimum, the length of the ports from the valve to the cylinder. 125

28. A pneumatic hammer having valve 130

- controlling ports; a combined automatic operating and throttle valve actuated by the pressure which it controls, supplied through said ports and constructed substantially as described to open the valve controlling ports at the ends of its strokes, and means arresting the valve before it opens the port at one end of its stroke whereby it is held by the pressure medium and the action of the hammer is stopped. 30
29. In a portable pneumatic hammer, a working cylinder and striking plunger; an automatic operating valve reciprocated by the pressure fluid, said valve being constructed and arranged to vary the rate of flow of the pressure fluid into the cylinder and also to vary the rate of transfer of the fluid from one end of the cylinder to the other; and means actuated independently of the valve for enabling the valve to effect both variations independently of each other, said means also enabling the valve to act as a throttle when the tool is not in action. 35
30. In a portable pneumatic hammer, a working cylinder and striking plunger; an automatic operating valve located directly above the end of the cylinder and in a position to admit pressure fluid to the upper end thereof and to transfer it to the lower end therethof; and means actuated by pressure and under the control of the operator to enable him to instantly vary the rate of flow of the air in its transfer from the upper to the lower end of the cylinder, said means being movable independently of the valve. 40
31. In a portable pneumatic hammer having an operating valve that is reciprocated by the pressure fluid; and means mounted on the handle of the tool and actuated independently of the valve, whereby the throw of the valve can be instantly changed at the will of the operator while the tool is in action. 45
32. In a portable pneumatic hammer having an operating valve that is reciprocated by the pressure fluid, means controlled by the fingers of the hand that grasps the handle of the tool whereby the throw of the valve can be changed instantly and independently in either direction while the tool is in use. 50

The foregoing specification signed at Jersey City Hudson Cy, this 16th day of February, 1906.

WILLIAM BAXTER, JR.

In presence of two witnesses—

RUTHERFORD LAVE,

THOMAS P. JOHNSTON.
